BEATING HEART TOY

David R. Uchill, Great Neck, N. Y.

Application July 9, 1951, Serial No. 235,719

3 Claims. (Cl. 46—117)

This invention relates in general to certain new and useful improvements in children's toys and, more particularly, to dolls and similar toy figures having a concealed sound emitting mechanism capable of simulating the sound of heartbeats.

Children are ordinarily intrigued and delighted with dolls which emit familiar sounds simulative of human sounds. Such sounds must, however, be generated by mechanisms which are substantially automatic and are very rugged inasmuch as children very quickly break toys which require winding or the manipulation of levers. Finally, the mechanism should, if possible, be entirely concealed to heighten the similarity to the human function being imitated.

It is the primary object of the present invention to provide a doll or similar toy with an internal mechanism capable of simulating human heartbeats.

It is another object of the present invention to provide a toy of the type stated in which the heartbeat simulating mechanism is rugged, durable, and entirely concealed.

It is an additional object of the present invention to provide a toy of the type stated in which the sound emitting mechanism is fully automatic and does not require winding or manual starting or stopping.

With the above and other objects in view, my invention resides in the novel features of form, construction, arrangement, and combination of parts presently described and pointed out in the claims.

In the accompanying drawings—

Figure 1 is a front elevational view of a doll constructed in accordance with and embodying the present invention;

Figure 2 is a front elevational view of a toy animal constructed in accordance with and embodying the present invention;

Figure 3 is a perspective view of the heartbeat simulating mechanism forming a part of the present invention;

Figure 4 is a sectional view taken along line 4—4 of Figure 3;

Figure 5 is a fragmentary sectional view taken along line 5—5 of Figure 4;

Figure 6 is a perspective view of the sounding board and associated components forming a part of the present invention;

Figure 7 is a vertical sectional view of a modified form of heartbeat simulating mechanism constructed in accordance with and embodying the present invention; and

Figures 8 and 9 are vertical sectional views taken along lines 8—8 and 9—9, respectively, of Figure 7.

Referring now in more detail and by reference characters to the drawings, which illustrate practical embodiments of the present invention, A designates a doll having a conventional exterior appearance including body, arms, legs, head, hair, and clothing. Concealed within the body of the doll A is a rectilinear box 1, including a front wall 2, top wall 3, side walls, 4, 5, bottom wall 6 and a rear wall 7. The box 1 may be made of any suitable material, such as a wood or fibre, but the rear wall 7 is

2

preferably made of a resonant substance so as to serve as a sounding board. Stapled or otherwise suitably secured to the outer face of the front wall 2 is a cloth strip 8 having laterally projecting tabs 9, 10, by which the box 1 may be stitched or otherwise secured upon the inside face of the doll's chest in a position approximately in the region where the heart is located in a human chest.

Rigidly fixed in and projecting forwardly from the rear wall or sounding board 7 into the interior of the box 1 just above the bottom wall 6 is a stud 11 and secured thereto by a pin 12 and looped therearound at its lower end is a relatively limber spring blade 13 which extends upwardly and at its upper end is provided with an enlarged weight or bob 14 so that the spring blade 13, in effect, becomes an inverted pendulum which will oscillate to-and-fro upon the slightest impulse resulting from movement of the doll A, as, for instance, when the doll A is picked up by the child during play. It should be noted that the spring blade 13 is presented edgewise toward the face of the sounding board 7 and in outwardly spaced relation thereto so that the bob 14 will oscillate along a path in outwardly spaced parallel relation to the sounding board 7, as best seen in Figure 5.

Riveted or otherwise suitably secured to the spring blade 13 adjacent the lower end thereof just above the pin 11 and extending equidistantly outwardly on opposite sides are somewhat flexible rocker-arms 15, 16, terminating above abutment members 17, 18, projecting perpendicularly outwardly from the sounding board 7. It will be noted by reference to Figure 4 that when the spring blade 13 is stationary in neutral position the rocker-arms 15, 16, are spaced from the abutment members 17, 18, respectively. Thus, when the bob 14 rocks back and forth, the rocker-arms 15, 16, will strike against the abutment members 17, 18, alternately, causing the spring blade 13 to bend somewhat and flip back with a form of spring-reaction which will prolong the pendulum-like response to each impulse. These movements will result in a tick-tock-sort of sound which is resonated from the sounding board 7 to simulate heartbeats when a child places her ear near or against the doll's chest. As the child plays with the doll A and handles it enough motion will result to impart an almost continuous series of impulses to the spring blade 13 and the latter is sufficiently sensitive so that the oscillations will continue for a relatively long interval after each impulse. Hence, the heartbeats will, in effect, be continuous while the doll A is in active use.

If desired, the box 1 may be similarly embodied in the animal toy B, as shown in Figure 2.

Similarly, if desired, a modified form of heartbeat mechanism may be provided which will continue to emit sound for a much prolonged period of time so that the heartbeats can be heard after the doll is laid down to sleep, for instance. The mechanism is mounted upon the interior face of a sounding board 7' which is substantially similar to the previously described sounding board 7. Screwed or otherwise suitably secured to the sounding board 7', as shown in Figure 8, is an auxiliary sounding board 19 provided with an upwardly extending metal plate 20 bent over at its upper margin in the formation of a flange 21 having a slot 22. Rigidly mounted at its lower end on a stud 11' by means of a pin 12' is a spring blade 13' having a bob 14' and lateral rocker-arms 15', 16', for impingement against abutment members 17', 18', all similar to comparable elements of the previously described embodiment. At its upper end the bob 14' is provided with a rod-like extension 23 which is adapted to swing back and forth in the slot 22 and within a bifurcated arm or yoke 24 fixed upon and projecting radially from a conventional one-way clutch barrel 25 operatively mounted on a vertically journaled shaft

3

26 having a bevel gear 27 meshing with a companion bevel gear 28 journaled on a main shaft 29, which is, in turn, journaled in the plate 20. Wrapped concentrically around and pinned at its inner end to the main shaft 29, is a main spring 30, which is also pinned at its outer end to the bevel gear 28. Fixed concentrically upon the main shaft 29 is a spur gear 31 which meshes with a pinion 32 keyed to an idler shaft 33. Also keyed on the shaft 33 is an escapement-wheel 34 operatively engaging an anchor pallet 35 attached to a lever 35^a which is notched at its end for operative engagement with a balance wheel disc 35^b keyed upon a rock-shaft 36. Conventionally attached at its inner end to the rock-shaft 36 is a hair spring 36' which is fixed at its other end to the plate 20.

The shaft 36 is journaled in and extends through the plate 20 in upwardly spaced parallel relation to the auxiliary sounding board 19. Pinned or otherwise rigidly secured to the shaft 36 is a sleeve 37 integrally provided with arms 38, 38', projecting radially on opposite sides thereof and respectively having enlarged hammer-elements 39, 39', formed of dense rubber or other suitable material for producing the desired timbre of sound upon impact against the auxiliary sounding board 19.

When a doll or other similar toy, equipped with the modified form of mechanism just above described, is moved about, the bob 14' will oscillate to-and-fro and will transmit energy through the yoke 24 and the one-way clutch to the bevel gears 27, 28, and wind the spring 30. The spring, as it is wound, will, in turn, release the energy stored in it slowly through the escapement-wheel 34 and escapement pawl 35 with a resultant rocking movement imparted to the shaft 36 which will, in turn, bounce the hammer-elements 39, 39', up and down against the auxiliary sounding board 19. Thus, the energy stored in the spring 30 while the doll is being handled and moved about will cause the heartbeats to continue for a long time after the doll is put down.

It should be understood that changes and modifications in the form, construction, arrangement, and combination of the several parts of the children's toy may be made and substituted for those herein shown and described without departing from the nature and principle of my invention.

Having thus described my invention, what I claim and desire to secure by Letters Patent is:

1. A toy simulative of an animate creature, said toy having a body, a hollow container concealed within said body, said container having a resonant wall, a pendulum operatively secured within the container, a journal-pin, a first gear journaled on the pin, a main spring wrapped concentrically around the pin and secured thereto at its one end, said spring being secured at its other end to the first gear, a shaft, a gear pinned to the shaft and adapted to mesh with the first gear, a one-way clutch element operatively mounted on the shaft, a yoke rigidly carried

by and extending radially from the clutch element, means extending from the pendulum into the yoke for transmitting the reciprocating movement of the pendulum to the yoke, a second gear rigidly mounted on the journal pin, a hair spring actuated escapement operatively connected to the second gear, and impact-hammers actuated by the escapement.

2. A toy simulative of an animate creature, said toy having a body with a torso-cavity wall, a hollow container having a resonant wall, said container being disposed entirely within the body, a fabric strip rigidly secured to and extending across the outer face of said resonant wall and projecting outwardly on either side thereof in the provision of tabs, said tabs being attached upon the inner face of the torso-cavity wall, a spring mounted at one end on the resonant wall, a weight attached to the other end of the spring and being free to oscillate in the nature of a pendulum, arms attached to the spring and extending laterally on opposite sides thereof, and abutment elements mounted on the resonant wall adjacent to the outer ends of the arms for receiving the impact of the arms as they are rocked responsive to oscillating movement of the spring, said abutment elements having contact faces of substantial area, said contact faces being positioned so as to be substantially parallel to the faces of the arms at moment of impact.

3. A toy simulative of an animate creature, said toy having a body with a hollow interior substantially enclosed by a body-forming wall, a hollow box having a flat wall of resonant material in the nature of a sounding board, said box being mounted wholly within the hollow interior of the body, a pendulum rockably mounted upon the sounding-board wall of the box and being free to bob back and forth as a result of motion imparted to the body when the latter is picked up and handled as the toy is being played with, arms attached to the pendulum and extending laterally outwardly on opposite sides thereof, and abutment elements mounted on the sounding-board wall adjacent to the outer ends of the arms for receiving the impact of the arms as they are rocked responsive to the oscillating movement of the pendulum, said abutment elements having contact faces of substantial area, said contact faces being positioned so as to be substantially parallel to the faces of the arms at moment of impact.
